HOME RECHARGEABLE LIQUID WAX INSECTICIDE AND FIRE-FIGHTING BOMB

John E. Shaffer, Brandon, Fla.

Application March 24, 1948, Serial No. 16,834

1. Claim. (Cl. 222—80.5)

1

This invention relates to a home rechargeable liquid wax insecticide or fire-fighting fluid bomb.

It is an object of the present invention to provide a fluid bomb which can be refilled at home when emptied instead of having to be returned to the dealer or factory and whereby to provide a bomb which is less expensive to use.

It is another object of the present invention to provide the user of the bomb with a handle and to render the bomb more safe in that the fluid, as the bomb is carried by the handle, will be sprayed directly away from the user.

It is another object of the present invention to provide a fluid bomb adapted for home use wherein the user of the bomb can insert different fluids in the same and thereby eliminate the necessity of having different bombs for different uses and wherein a bomb will have a separable gas charging cartridge which will be disposed within the interior of the bomb instead of outside thereof whereby to eliminate the possibility of gas blowing back into the user's face as may happen when the cartridge is located on the outside of the bomb.

Other objects of the present invention are to provide a home rechargeable liquid wax, insecticide and fire-fighting fluid bomb which is of simple construction, inexpensive to manufacture, convenient to use, easy to fill and charge, and efficient in operation.

For other objects and for a better understanding of the invention, reference may be had to the following detailed description taken in connection with the accompanying drawing, in which:

Fig. 1 is a vertical sectional view taken through the bomb embodying the features of the present invention and through the operating parts thereof.

Fig. 2 is an enlarged sectional view, in elevation, taken through the cartridge chamber and with the cartridge elevated to have its valve depressed to extend the gas into the bomb.

Fig. 3 is an enlarged sectional view, in elevation, taken through the outlet valve structure for the bomb with the button in the depressed position and the valve open.

Fig. 4 is a transverse sectional view taken on line 4—4 of Fig. 3.

Fig. 5 is a fragmentary bottom plan view of the bomb looking on line 5—5 of Fig. 1.

Fig. 6 is a fragmentary elevational view of a modified form of top structure with a nozzle extended therefrom.

Fig. 7 is a sectional view, in elevation, of a modified form of cartridge housing including a

2

triangular pronged puncturing element for the capsule.

Fig. 8 is a transverse sectional view taken on line 8—8 of Fig. 7.

5 Referring now to the figures, 15 represents a container adapted to receive the liquid wax, window cleaning fluid, insecticide or fire-fighting fluid which is to be dispensed by the same. The upper part of the container is flattened as indicated at 16 to permit the use of the handle 17 secured thereover.

The bottom of the container is dished as indicated at 18 and has secured to it an internally threaded sleeve 19 adapted to receive a plug 21 having handles 22 thereon. When this plug 21 is removed from the sleeve 19, access can be had to a capsule or cartridge disposed in a cup-shape member 23 on the inner end of the sleeve 19 and with a perforated bottom as indicated at 24. The cartridge is indicated at 25. This cartridge has a bushing or ball valve structure 26 on its inner end adapted to receive a pin 27 on the bottom 24. This pin may extend into the ball valve structure for engagement with ball valve element 28 to remove the same from the seat against the action of a spring 20. The cartridge 25 is normally maintained in its non-projected position by a spring 31 which reacts against the bottom 24.

30 The sleeve 19 has a radially inwardly extending flange 32 against which may rest a diaphragm 33 which seals the cartridge 25 within the sleeve 19. This diaphragm is backed up with a washer 34 and the plug 21. Extending through the center of the plug 21 is a push button 35 having an enlarged head 36 which engages with the diaphragm to cause the diaphragm to be pushed inwardly as shown in Fig. 2 for moving the cartridge to the position shown in Fig. 2 whereby the pin 27 will engage with the ball 28 to open the cartridge and to cause the container 15 to be charged with the gas. When sufficient gas has been let into the container, the bomb is ready for use.

45 When the plug 21 and the diaphragm 33 and the cartridge 25 have been removed, the desired fluid can be disposed in the container 15.

In the top of the container there is depressed inwardly a sleeve portion 38 adapted to receive a cup-shaped member 39 having a flange 41 resting on the top of the container and secured thereto by solder 42. The upper end of the cup-shaped member is externally threaded as indicated at 43 to receive an inverted cup-shaped member 44 which can be screwed thereupon.

Within the member 44 is a plug 45 having a central opening 46 through which extends a pin 47 adapted to engage with a ball 48 which is normally maintained on its seat 49 by a spring 51 disposed within the member 39. Extending from the bottom of the member 39 are liquid tubes 52 and 53 having respectively screened ends 54. On the upper end of the plug, there is a diaphragm 56 which provides a seal. The pin 47 extends to the diaphragm. Above the diaphragm is a plate 57 through which may be operated a push button 58 having a pin projection 59 adapted to engage the opposite side of the diaphragm 56. The ring 61 serves to retain the push button within the ends of the member 44.

Within the plug 45 is an annular groove 62 to which fluid is dispensed through a radially extending passage 64 from the opening 46 as the ball 48 is depressed. In the member 44 is an outlet opening 65 at the level of the groove 62 through which the fluid will be discharged to the atmosphere. The button 58 can be reached with the thumb while grasping the handle 17. The plug 45 can be held against rotational displacement within the member 44 by keys 67. Fig. 4.

In the design shown in Figure 6, which is particularly adapted for fire extinguishing fluids, a container 68 is provided with a cup-shaped member 69, similar to the member 44, and this member is provided with a fire nozzle or nipple 69 through which the fluid may be ejected or sprayed as a button 70 on the upper end is pressed downward.

The design illustrated in Figures 7 and 8 is particularly adapted for a cartridge of the bottle neck type and the container is provided with a sleeve 71 similar to the member 23, and the upper perforated end 72 thereof is provided with a three cornered prong 73 that extends downward to engage and puncture the upper end 74 of a cartridge 75. The cartridge is held downward by a spring 76, similar to the spring 31 until it is forced upward by the pin 35. The lower end of the cartridge 75 is provided with a filling opening 77 in a threaded neck 78 and the opening is provided with a closure or plug 79, as shown.

It will be understood that although the device has been described as a bomb it may be used for liquid wax, insecticide, window cleaning fluid, fire extinguishing fluid, or any substance desired, and any suitable means may be provided for creating or providing pressure therein.

It will also be understood that modifications may be made in the design and arrangement of the parts without departing from the spirit of the invention.

I claim:

In a fluid bomb, the combination which comprises a container having a handle on one side and an arcuate web forming a bottom in one end, 5 a button actuated outlet nozzle extended from the end of the container opposite to that in which the bottom is positioned, an internally threaded sleeve with an inwardly extended annular flange in the inner end mounted in the said arcuate web 10 forming the bottom of the container and extended inwardly into the container, an elongated cup-shape member having a perforated inner end extended inwardly from the said sleeve and having a centrally disposed pin extended from the 15 said perforated inner end into the interior thereof, a cartridge having a bushing with an opening therethrough in one end in the said cup-shape member and held with the opening of the bushing therein positioned to receive the said pin extended from the end of the cup-shape member, a spring actuated ball in the said bushing and positioned to coact with the opening therethrough providing a valve, a spring in the cup-shape member positioned to urge the cartridge 20 away from the said pin, a diaphragm extended across the inner end of the said sleeve carried by the arcuate web forming the bottom of the container, a plug having a centrally positioned opening therethrough and handles extended 25 therefrom threaded in the said sleeve, and a button extended through the opening of the plug and having a head on one end positioned with the head adapted to urge the diaphragm against the cartridge whereby the cartridge is moved inwardly by the button with the pin of the cup-like member passing into the opening of the bushing, unseating the ball and opening the valve therein.
